RUFFLE FOLDER

Phillip Krauss, Memphis, Tenn., assignor to Robert Van Cleeff and Samuel J. Behr, a partnership doing business as The Fashion Curtain Company, Memphis, Tenn.

Application March 6, 1944, Serial No. 525,161

1 Claim. (Cl. 112—147)

This invention relates to improvements in folding and guiding devices, such as are used in the folding of edge portions of ruffles in making curtains, and the subsequent guiding of these edge portions to place and holding them in proper position during the stitching of the ruffle to the edge of the curtain body.

In attaching ruffles to dresses, or more extensively, the attaching of ruffles to the edge portions of curtains, guides, usually known as folders, have been developed which for purposes of distinction may be designated as body folders which turn in and guide an edge portion of the body of the curtain, and an additional guide or ruffle folder which turns in and guides the edge portion of the ruffle which is to be attached to the curtain, these two folders being set up in overlying relation so that the edges of the body and of the ruffle may be brought into proper juxtaposition and the ruffle then tucked or gathered as it is fed to a stitching or sewing machine and the two parts secured together.

It has long been known to hem the edges of the ruffle and to fold and guide one of these hemmed edges into position, the stiffening of the ruffle edge by hemming making it comparatively easy to accomplish the guiding and feeding of the ruffle edge after it has left the ruffle folder and is being engaged by the tucker.

There has, however, been developed a ruffle in which an unhemmed edge is folded back on the ungathered ruffle strip, and, without stitching, this loosely disposed and flimsy edge is assembled over the edge of the body portion and after being gathered by the tucker is stitched to the folded-in raw edge of the body portion in such manner that the two raw edges lie between the lines of stitching and an edge portion of the ruffle projects from the stitching oppositely to the much wider portion of the ruffle proper, such ruffle finish and attachment to the body edge of the material being shown in the patent to Wright, No. 2,246,197, issued June 17, 1941.

In this type of ruffle, folding of the body edge is readily performed by well known devices, and with such the present invention is not concerned.

Folding and guiding of the attaching edge of the ruffle shown in this patent, however, proved in commercial manufacture to be extremely difficult and much time, thought, and experimentation were given before accomplishment of this apparently simple problem was solved.

The primary object of the present invention is:

To provide a folder which will maintain and guide the loose and extremely flimsy edge por-

tion of the ruffle as nearly as possible to the point where it is taken over by the tucker bar of the machine and thereby gathered and advanced into desired relation with the underlying ungathered body portion of the curtain, and the juxtaposed ruffle and body edges brought within the influence of the presser foot of the sewing machine and the usual underlying advancing mechanisms by which movement to the needles for sewing 10 is effected.

The means by which the foregoing and other objects are accomplished, and the manner of their accomplishment, will readily be understood from the following specification upon reference 15 to the accompanying drawings, in which:

Fig. 1 is a perspective view of a fragmentary portion of the head end of a double needle type of sewing machine through which ruffle attachment to the curtain edge is effected, with my 20 improved folder in working attachment thereto.

Fig. 2 is a plan view of the folder.

Fig. 3 is an elevation of the front or feed-in side.

Fig. 4 is a side elevation looking in the direction 25 of the arrow IV of Fig. 2.

Fig. 5 is a sectional side elevation taken on the line V—V of Fig. 2; and

Fig. 6 is a section on the line VI—VI of Fig. 2.

Referring now to the drawings in which the 30 various parts are indicated by numerals:

11 is part of the head of a sewing or stitching machine, 13 the presser foot, 15 the throat plate, 17 a pair of needles which are carried by the usual needle holder 19 and reciprocated by mechanism within the head, the needles passing in usual manner through the presser foot and throat plate.

21 is a tucker or gatherer bar which is reciprocated, in entirely usual manner, by an arm 23, 40 the movement of which arm is coordinated with the needle movement. The end 21A of the tucker bar is corrugated and overlies a tucker plate 25, and when the bar is reciprocated by the arm 23, the corrugated end engages and advances interposed material with a step by step movement. The ruffle overlies the plate 25, and the body material to which it is to be attached underlies the same plate, the tucker bar engaging and pushing the edge of the ruffle past the end 45 of the plate 25 and against the underlying body material in immediate proximity to the presser foot 13, from which point other portions of the machine feed mechanism take over and move the two pieces jointly into position where they

50 are stitched by action of the needles 17. The 55

edge 27 of the body material 29, Fig. 2, is folded over and guided as it is approached toward the presser foot 13 by attachments, which form no part of the present invention and are, therefore, not shown.

Depending from the head 11 is a support 31, to which the instant ruffle folder, generally indicated by the numeral 33, is attached, attachment being effected by a U clip 35, integrally attached to the folder, which clip embraces the support 31 and is clamped thereto by a set screw 37. The support 31 includes an inwardly extending part 39 which supports and carries the plate 25 along which the tucker bar is reciprocated.

The folder 33 comprises a thin plate-like leaf 41, best seen in Fig. 6, which extends horizontally away from the U member 35. At its inner edge 41A the leaf is folded under and outward along and against itself, the two thicknesses being preferably integrated by soldering or brazing into a double thickness section 42, the underlying portion being then downwardly and inwardly bent at 41C to form a guiding bight and the leaf portion 41D continued inward parallel with the overlying portions to establish a throat 43. The inner edge of the leaf portion 41D is upwardly curved at 41E concentrically around the edge 41A to form an arcuate throat 43A and is continued outward at 41F in overlying relation to the leaf 41, continuing the throat 43A outward and establishing a major throat portion 43B opening away from the U member 35, these throat portions forming a throat which in cross section is substantially a slender J and folding and guiding the ruffle 44 (Fig. 2). Rigid securing of the guiding portions of the folder to the clip portion 35, is effected along the curved portion 41E. Preferably the front, or feed-in edges of the plate-like leaf portions are, as shown in Fig. 5, thickened to effect stiffening.

Fore and aft the depth of the folder is such that the front edge may be positioned forward of the tucker arm 23 and the rear edge substantially flush with the rear edges of the clip 35 and support 31, but there terminates to avoid confinement of the ruffle 44 as it is gathered, and avoid interference with action of the tucker bar 21. The center section 42, and the over and underlying leaf portions 41F and 41D, however, are provided with rearward tongue extensions 42X, 41X, 41Y respectively, reduced in width to avoid interference with the tucker bar 21, and the curved portion 41E joining the leaves 41F, 41D with a like extension 41Z, and establishing an arcuate throat extension 43X of the arcuate throat 43A. This throat extension is carried rear-

wardly into close adjacency with the outward end of the path of the tucker bar end 21A to provide guidance within and without of the inherently flimsy edge of the ruffle.

In Fig. 2, the dotted lines 51 indicate the positioning of the stitching relatively to the edges of the ruffle and body portions of the material 44 and 29 respectively.

In using the folder, the cloth 29, Fig. 2, forming the body of the curtain is fed in through a usual type of folder, not shown, which folds the edge 27 of the body upward and over on the body forming a narrow edge, which is drawn in a straight line toward the needles 17, and lends itself to easy guidance. At the same time the cloth 44 forming the ruffle is fed into the J-shaped throat formed by the slot portions 43, 43A, 43B of the folder until engagement is secured with the edge 21A of the tucker bar 21, after which advancement is taken over by the bar. In passing through the folder the edge 44A of the ruffle is folded under and against the ruffle body to form a leafed ruffle heading 44B, which, owing to the flimsiness of the material and the depth of the heading, is extremely hard to guide, and which additionally must be gathered by a tucker bar which is off-set away from the edge of the heading. Guidance for this heading is effected substantially to the point of tucker bar engagement by the central tongue extension 42X and the narrow over and underlying plate extensions 41X and 41Y and their connecting arcuate extension 41Z.

I claim:

35 In a machine for attaching ruffles to a body member, which machine includes a head, stitching means, a tucker plate, a tucker bar spaced at its outward end above said plate and converging inwardly and downwardly to a gathering end proximate to said plate, and means for reciprocating said bar; a folder and guide for flimsy ruffle material, which said folder is of relatively much greater width than said tucker bar, and includes members forming a substantially J-shaped slot having its longer leg open, and its shorter leg closed, disposed below said bar, with the bight portion of said slot extending laterally therebeyond, said members being cut away to provide a continuation of said laterally extending bight portion alongside said bar, with the open side of said bight facing said bar, into adjacency to the end of the path of inward movement of said bar, whereby to guide the folded edge of said flimsy material substantially to stitching position.

PHILLIP KRAUSS.
